CLAIM

The ornamental design for an oil burning candle apparatus, as shown and described.

DESCRIPTION

FIG. 1 is a top and front perspective view of a first embodiment of an oil burning candle apparatus.

FIG. 2 is a front view of the embodiment of the apparatus of FIG. 1.

FIG. 3 is a side view of the embodiment of the apparatus of FIG. 1.

FIG. 4 is a top view of the embodiment of the apparatus of FIG. 1.

FIG. 5 is a bottom view of the embodiment of the apparatus of FIG. 1.

FIG. 6 is a top and front perspective view of the embodiment of the apparatus of FIG. 1, showing a volume of oil within the apparatus in dashed lines.

FIG. 7 is a top and front perspective view of a second embodiment of an oil burning candle apparatus.

FIG. 8 is a front view of the embodiment of the apparatus of FIG. 7.

FIG. 9 is a side view of the embodiment of the apparatus of FIG. 7.

FIG. 10 is a top view of the embodiment of the apparatus of FIG. 7.

FIG. 11 is a bottom view of the embodiment of the apparatus of FIG. 7.

FIG. 12 is a top and front perspective view of the embodiment of the apparatus of FIG. 7, showing a volume of oil within the apparatus in dashed lines.

FIG. 13 is a top and front perspective view of a third embodiment of an oil burning candle apparatus.

FIG. 14 is a front view of the embodiment of the apparatus of FIG. 13.

FIG. 15 is a side view of the embodiment of the apparatus of FIG. 13.

FIG. 16 is a top view of the embodiment of the apparatus of FIG. 13.

FIG. 17 is a bottom view of the embodiment of the apparatus of FIG. 13; and,

FIG. 18 is a top and front view of the embodiment of the apparatus of FIG. 13, showing a volume of oil within the apparatus in dashed lines.

The broken lines in the drawings show portions of the oil burning candle apparatus that form no part of the claimed design. The drawings include a separation and gap in the

length of portions of the article which represent a symbolic break in length of the oil burning candle apparatus. The appearance of any portion of the article between the break lines forms no part of the claimed design.
